GAS FLOWMETER

James A. Huggins, Libertyville, Ill., assignor to Baxter Laboratories, Inc., Morton Grove, Ill.

Filed Apr. 9, 1971, Ser. No. 132,924

Term of patent 14 years

Int. Cl. D10—04

U.S. Cl. D52—6

FIG. 1 is a front perspective view of a gas flowmeter showing my new design;

FIG. 2 is a top plan view thereof;

FIG. 3 is a left side elevational view thereof;

FIG. 4 is a vertical half-sectional view thereof.

I claim:

An ornamental design for a gas flowmeter, substantially as shown.
